WINDING DEVICE FOR TOPS

Hermann Schmidt, Berlin-Reinickendorf-Ost,
GermanyApplication October 25, 1934, Serial No. 749,969
In Germany March 21, 1931

2 Claims. (Cl. 46—32)

This invention relates to a top winding device and differs from the known devices in this, that the winding device consists of two parts which are capable of turning about a common axis in 5 opposite directions, viz: an upper rotatable part and a lower holding part. Through this division into two parts the disadvantages from which the known devices serving the same purpose suffer are done away with, which consisted in this, that, 10 on the one hand the winding devices had to be pressed so firmly against the top that far too much force had to be exerted, or that, on the other hand, it was necessary for the top peg to be released at exactly the right moment, which 15 it was not easy to time. Furthermore, the release of the winding up spring has hitherto been effected by pressing on the top peg or on a knob connected to the locking pin, but not so that the device need only be placed on the top and lightly 20 pressed against it, in order to set the top in rotation. This requirement is also fulfilled by the present invention thus enabling the top to spin for a considerable time.

The invention is illustrated diagrammatically and by way of example in the drawing in vertical section, 1 is the upper rotary part and 2 the holding part disposed under it. In the axis of both parts are disposed the tubes 3, 4 which are fixed in the rotary part and on the bottom flanges 30 of which the holding part 2 rests lightly. Between the two tubes is the helical spring 6 which is fixed at its upper end at 5 and terminates at the bottom, where it projects from the holding part, in the hook 7, being prevented by the flange 35 of the inner tube 3 from falling out.

The rotary part 1 is further provided with the spring loaded pin 8 which engages in a recess 9 of the holding part, while the holding part 2 is provided on one side with a spring loaded pin 10 40 which can be fixed in position behind a part 13 of the bottom of the holding part by means of a lateral projection 11 which slides in a slot 12. On the other side the holding part is provided with laterally spring loaded pins 14, 15 which are rigidly connected in a U-shaped manner and of which the shorter pin 14 engages behind the hook 7 of the winding up spring, while the longer pin 15 projects out of the bottom surface of the holding part. A lateral projection 16 on the pin 15, which is sliding in the slot 17 enable the pins 14, 15 which are prevented from moving freely by the spring which acts on them, to be adjusted according to requirement.

The new device operates in the following manner:

For causing the top to spin the locking pin 10 is fixed behind the shoulder 13 and the U-shaped structure 14, 15 is pushed downwardly. The holding part is then held firmly with the left-hand and the rotary part is turned with the right hand, until the spring is stressed. The winding up device is then placed on the top and lightly depressed, causing the pin 15 to engage the upper surface of the top and to be slid upwards. At the same time the pin 14 releases the spring hook 10 5. The latter thereupon engages in an opening in the upper surface of the top and carries the top round with it. After the spring has expanded, the spring hook 7 leaves the opening, the device is raised and the top will spin. 15 For causing the top to spin continuously the device with the spring stressed is placed, as already described, on the top, being depressed with a short pressure and raised again. This action can be repeated and the top thus kept spinning 20 as long as desired.

If the top is to be used as a jumping top, the locking pin 10 is moved by means of the sliding member 11 into the operative position, the device is wound up independently of the top, is placed 25 on the latter so that the locking pin 10 engages in it and the device is pressed lightly down on to the top, thereby causing the spring hook 7 to be released from the retaining pin 14 and to engage in one of the openings in the top. The hand 30 holding the top is then extended and the sliding member 11 pushed up by means of the forefinger, causing the locking pin 10 to be disengaged, the spring hook of the expanding spring to carry the top round with it and the top to drop to the 35 ground.

When the top is being used as a jumping top, the winding up device may be wound up by sliding up the pins 14, 15, bringing the locking pin 10 into the operative position and placing the whole 40 of the winding up device on to the top and turning it, when the spring hook 7 will engage in one of the openings in the body of the top and the spring will become stressed. In contradistinction to the known constructions it is not necessary to 45 press the body of the top against the winding up device, as the lower flange of the inner tube 3 does not allow the spring to come out. The top and the winding up device are then held in the extended right hand and the sliding member 10 is 50 brought into the position of rest, causing the top to rotate and to fall down.

What I claim is:

1. A winding device for tops comprising a holder member and a rotary member rotatably mounted 55

on said holder member, a helical spring provided with a hooked end adapted for engaging a top and disposed centrally through said members and fixed at one end to the rotary member, means for detachably securing the other end of said spring to the holder member whereby the spring may be tensioned by rotating the rotary member in one direction with respect to the holder member, means disposed in said rotary member for preventing the release of the spring and means

disposed in said holder member actuated by placing the device on the top for releasing the spring and thereby effecting engagement of the said hooked end with the top whereby the top is set in motion.

2. A device as claimed in claim 1 comprising means for releasably securing the device to the top whereby the top may be released and spun from an elevated position.
